Des. 225,738
Patented Jan. 2, 1973

225,738

AIR CLEANER COVER

Edwin L. Schwartz, Los Angeles, Calif., assignor to Rite
Autotronics Corporation, Los Angeles, Calif.

Filed June 17, 1970, Ser. No. 23,538

Term of patent 14 years

Int. Cl. D23—04

U.S. Cl. D23—149

FIG. 1 is a top plan view of the air cleaner cover showing my new design;

FIG. 2 is a sectional view along line 2—2 of FIG. 1;

FIG. 3 is a side elevational view;

FIG. 4 is a bottom plan view.

I claim:

The ornamental design for an air cleaner cover, substantially as shown.
